UNITED STATES PATENT OFFICE.

HARVEY C. WHEELER, OF BOSTON, MASSACHUSETTS.

TOWEL-CABINET.

No. 825,436.

Specification of Letters Patent.

Patented July 10, 1906.

Application filed September 15, 1905. Serial No. 278,656.

To all whom it may concern:

Be it known that I, HARVEY C. WHEELER, a citizen of the United States, and a resident of Boston, in the county of Suffolk, Commonwealth of Massachusetts, have invented certain new and useful Improvements in Towel-Cabinets, of which the following is a full, clear, and exact description.

The object of this invention is the construction of an improved device for supporting an elongated strip of toweling by means of rollers attached to the ends thereof, by means of which a fresh section of the same can be kept constantly presented until the whole has been used.

Referring to the drawings forming part of this specification, Figure 1 is a side sectional elevation of a cabinet embodying my improvements. Fig. 2 is a similar sectional view of the lower part of said cabinet, but showing the toweling wholly retired from access. Fig. 3 is a similar view, but showing the toweling put out of sight, although capable of being taken out by simply opening the door of the cabinet. Fig. 4 is a detail view of one end of one of the towel-rollers. Fig. 5 is a similar view of the opposite end of such roller. Fig. 6 is a side view of an end of the space-roll, showing its bearing.

The general appearance of the cabinet 1, to which my improved towel-supplying arrangement is applied, does not greatly vary from those which I have previously made and put upon the market; but within the lowermost compartment 5 thereof is located the towel-rollers 10 and 16, to which are affixed the ends of the long strip of toweling T. These rollers are rotatively supported within recesses formed in the sides 8, as shown in Figs. 4 and 5, a trunnion 11 at one end of each roller entering the recess 12, and a removable knob 17, penetrating the opposite side and having spurs 19 entering suitable openings therefor in the roller end, being provided for the other end of each roller. By removing said knobs the rollers can be easily withdrawn for replacing the soiled towel with fresh. My preferable means for attaching the ends of the toweling to the rollers consist of tacks or screws 14, permanently fixed in the rollers and engaging buttonholes 15 in the cloth. This arrangement is inexpensive and at the same time efficient, while the buttonholes or other eyes do not interfere with the laundry work upon the toweling. By turning said knobs the cloth

can be wound up on one roller and unwound from the other until the desired amount is exposed for use.

I prefer to have the towel issue from the upper front part of the compartment 5 for the reasons hereinafter set forth, providing for such purpose a roll or bar 30 between the top edge of the compartment front 7 and the under surface of the shelf 3. Between the two narrow slits thus formed issue the two lengths of the towel, as shown in Fig. 1. This roll 30 is made removable by providing the trunnion 31 at one end thereof with a recess 33 sufficiently elongated vertically to permit such end to be lifted free therefrom and the whole roll withdrawn. The shelf 3, being hinged at its rear edge, can be thrown back and so out of the way. (See Fig. 6.)

Ordinarily the section of towel when not in use is folded up and back upon the shelf 3 and the door 4 closed; but when in use the door is open and the towel-section hanging, as shown in Fig. 1.

It often happens that an office proprietor does not care to have other parties use any part of the towel in his cabinet, while still willing to have them use the mirror on the interior of the cabinet-door and whatever other toilet appliances may be contained upon the shelf 2 of the cabinet. To provide for such, the shelf 3 is provided with a lock and key, (indicated at 40 in Fig. 2.) The office proprietor then simply removes the roll 30 and tucks the towel-section within the compartment 5, afterward returning the roll to its place and locking the shelf 3 down in position. This effectually secures the towel against use by any one else.

What I claim as my invention, and for which I desire Letters Patent, is as follows, to wit:

1. A cabinet provided with a towel-compartment in its lower end, a shelf forming the top of said compartment, a space being allowed between said shelf and the top edge of said compartment's front, one or more rollers located in said compartment, toweling secured to the same and extended outward through said space, and a door for said cabinet reaching below said space; whereby the towel can be folded back upon said shelf when not in use, and the door when closed will also shut in said space.

2. A towel-cabinet provided with a compartment in its lower end, a shelf forming the top of said compartment, a space being

allowed between said shelf and the top edge of said compartment's front, a bar located in said space, a pair of rollers within said compartment, and a length of toweling terminally secured to said rollers and passing out and in through said space above and below said bar.

3. A cabinet provided with a towel-compartment in its lower end, a movable shelf forming the top of said compartment, a space being allowed between said shelf and the top edge of said compartment's front,

rollers located in said compartment, toweling secured thereto and extended outward through said space, a door for the cabinet reaching below said space, and means for locking said shelf in position.

In testimony that I claim the foregoing invention I have hereunto set my hand this 13th day of September, 1905.

HARVEY C. WHEELER.
